EDUCATIONAL MUSICAL TOY CLOCK

Duane E. Spengler, West Falls, N.Y., assignor to Fisher-
Price Toys Incorporated, East Aurora, N.Y., a corporation of New York

Filed Feb. 27, 1963, Ser. No. 73,741

Term of patent 14 years

(Cl. D34—15)

FIG. 1

FIG. 3

Des. 198,756

FIG. 1 is a front elevation of an educational musical toy clock, showing my new design;

FIG. 2 is a side elevation thereof,

FIG. 3 is a top plan view thereof, and

FIG. 4 is a back elevation thereof.

The dominant features of my design reside in the portions shown in full lines.

I claim:

The ornamental design for an educational musical toy clock, substantially as shown and described.
